UNITED STATES PATENT OFFICE.

DOCTOR F. MORGAN, OF AKRON, OHIO.

SECTIONAL STEAM-BOILER.

SPECIFICATION forming part of Letters Patent No. 379,975, dated March 27, 1888.

Application filed July 18, 1887. Serial No. 244,667. (No model.)

To all whom it may concern:

Be it known that I, DOCTOR F. MORGAN, a citizen of the United States, and a resident of the city of Akron, in the county of Summit 5 and State of Ohio, have invented a new and useful Improvement in Sectional Steam-Boilers, of which the following is a specification.

My invention has relation to improvements in cast-iron sectional boilers for heating purposes.

The objects of my invention are to increase the heating capacity of the boiler by placing the magazine outside of the sections and utilizing the part usually occupied by the magazine for heating, to provide facilities for cleaning the heating-surfaces from soot and ashes, and by a peculiar form of fire-pot section limit the area of the burning fuel and secure its more perfect combustion.

My invention consists in the devices illustrated in the accompanying drawings, as hereinafter described and claimed.

In the accompanying drawings, Figure 1 is a side elevation of a complete boiler embodying my invention; Fig. 2, a vertical central section of the same; Fig. 3, a plan of the same; Fig. 4, an inverted plan of the top section or steam-dome; Fig. 5, a plan of one of the water-sections between the dome and fire-pot; Fig. 6, a side elevation of two of the same; Fig. 7, a view of cleaning-tube G, hereinafter referred to, which is interposed between the sections; Fig. 8, a door for the tube G, with partitions hereinafter explained; Fig. 9, a cross-section of one of the radial arms of the sections E, and Fig. 10 a plan of the fire-pot section.

Referring to the drawings, A is a hollow base, which forms the ash-pit, supports the 40 grate a, is provided with doors a' a'', for removing ashes and reaching the grate, respectively, and has an annular flange, c, about its top, on which the boiler-case C rests. Upon this base is the fire-pot section B, which consists of a 45 deep hollow ring having in its upper face water-ports e and curved outwardly-turned notches f', which register, respectively, with the water-ports e and flues f of the next upper section. Through this section on opposite sides, and vertically coincident with two of the notches f', are two openings, h, which pass obliquely downward toward the center

of the grate, at each of which points the part of the section which constitutes the lower face of the opening extends in the same line inward 55 for a short distance beyond the inner line of said section, and thence recedes outward, as shown in Figs. 2 and 10.

By this construction the fuel from the magazines, hereinafter described, is delivered near 60 the center of the grate, which tends to retain the fire at that point, and the receding faces of the section prevent the grate becoming choked with ashes and permit the air to pass upward through the burning fuel, thereby securing a 65 more perfect combustion than if they were not thus formed.

Above the section B are a series of sections, E, similar in construction, each consisting of a hollow ring and a hollow closed hub, E', connected by hollow spokes, heart-shaped in cross-section, as shown in Fig. 9, through which ring smoke-flues f pass and into which water-ports e enter at regular intervals and register with the flues and ports of adjacent sections. 75

The hubs E' are of less depth vertically than the outer ring, so that hubs of adjacent sections do not touch; but a space is left between them, through which the products of combustion pass, thereby increasing their heating-surface. 80

The spokes differ in number with the flues and ports, so that in "building up" the boiler the spokes of adjacent sections may alternate vertically. 85

In the upper and lower face of each ring E, across one of the smoke-flues, is a semi-elliptical notch, g, so arranged that notches of adjacent sections shall register and form an opening by which the inner heating-surfaces of the 90 sections may be reached and cleaned. Opposite these openings are similar openings in the outer case, C, in each of which is a tube, G, Fig. 7, which extends to the inside of the ring of the section E and has slots in its upper and 95 lower faces coincident with the smoke-flues.

The end of each tube G is closed by a door, I, from the inside of which projects a rod bearing two plates, i i', which fit the inside of the tube G and close it on each side of the smoke-flue f, thereby preventing communication through the tube between the smoke-flue and the center of the sections E, or the space between them and the case C. 100

The steam-dome D consists of a hollow section with a concave base and convex top supported by its outer lower edge on the top section, E, provided with water-ports e^2 , which 5 project down and meet and register with the ports e of the next lower section, a direct-draft flue, F, and a flange, c' , about its outer upper edge, to hold the upper edge of the case C. The case C between the flanges $c c'$ incloses the 10 boiler, and has near its top an uptake-flue, F^2 , with which the direct-draft flue F unites, in which latter is a damper, F'.

On opposite sides of the boiler are two magazines, H H, which enter the openings in the 15 section B, and thence extend upward along the case C, their upper ends being closed with doors.

In operation the magazines are charged with fuel, which descends by gravitation onto the 20 grate. When the fire is first started, the damper F' is open and a direct draft is produced inside of the outer rings of the sections E and out through the flue F; but as the boiler becomes heated this damper is closed and the products 25 of combustion pass up inside of the outer rings of the sections E until they reach the dome D, thence down through the smoke flues f, and again upward between the case C and sections E to the uptake-flue F.

30 I claim—

1. In a boiler of the class designated, the combination, with a fire-pot section, as B, having side openings, as h , the lower faces of which

incline down toward the center and project beyond the inner line of the section, of magazines, as H, which unite with said openings and extend upward outside the boiler, substantially as shown, and for the purpose specified. 35

2. The combination, in a boiler of the class designated, of the grate a , the water-section 40 B, having side openings, h , with lower faces which project beyond the inner line of said section, the magazines H, united with said openings, and sections E, resting on said section B, all constructed and arranged substantially as shown, and for the purpose specified. 45

3. The combination, in a boiler of the kind designated, of a series of water-sections, each consisting of a hollow ring provided with water-ports and smoke-flues, and a hollow closed 50 hub less in vertical depth than said ring and united therewith by hollow spokes, substantially as shown, and for the purpose specified.

4. In a boiler of the kind specified, the combination, with the sections E, having notches 55 g , and the case C, having openings opposite said notches, of the tube G, door I, and plates $i i$, all constructed and arranged substantially as shown, and for the purpose specified.

In testimony that I claim the foregoing I have 60 hereunto set my hand.

DOCTOR F. MORGAN.
